UNITED STATES PATENT OFFICE.

DAVID J. SEAMAN, OF SOUTH BEND, INDIANA.

DESIGN FOR A FABRIC.

SPECIFICATION forming part of Design No. 34,303, dated March 26, 1901.

Application filed February 28, 1901. Serial No. 49,356. Term of patent 14 years.

To all whom it may concern:

- Be it known that I, DAVID J. SEAMAN, a citizen of the United States of America, residing at South Bend, in the county of St. Joseph 5 and State of Indiana, have invented and produced a new and original Design for Fabrics, of which the following is a specification, reference being had to the accompanying drawing, forming a part hereof.
- 10 This design relates to the ornamentation of cotton, silk, woolen, paper, celluloid, and other fabrics.
- In the drawing I have shown a plan view of my design.
- 15 The leading feature of the design is the representation of stems running along or upon the surface of the fabric in two parallel adjacent paths and holly-leaves lying upon and springing from the stems and interspersed

with holly-berries. The stems A appear in two groups running parallel to each other and following pronounced waves or compound curves, the stems in each group being twisted or given a sinuous shape along the said compound curved paths. Holly-leaves B appear lying upon and rising from the stems, and berries C appear on the stems in the intervals between the leaves.

What I claim is—

The design for a fabric described and shown. 30

In testimony whereof I have signed this specification in the presence of two attesting witnesses.

DAVID J. SEAMAN.
